UNITED STATES PATENT OFFICE.

IVAR G. BERGENSTROHLE, OF WORCESTER, MASSACHUSETTS.

POCKET SAFETY DEVICE.

978,106.

Specification of Letters Patent.

Patented Dec. 6, 1910.

Application filed October 12, 1909. Serial No. 522,342.

To all whom it may concern:

Be it known that I, IVAR G. BERGENSTROHLE, a citizen of the United States, residing at Worcester, in the county of 5 Worcester and State of Massachusetts, have invented a new and useful Pocket Safety Device, of which the following is a specification.

This invention relates to a device for retaining articles in the pocket and preventing their accidental loss, and also for preventing them from being stolen without giving sufficient notice to the owner.

The invention also involves the provision 15 of means for accomplishing this result, constructed in a very simple manner and of inexpensive materials.

Further objects and advantages of the invention will appear hereinafter.

Reference is to be had to the accompanying drawings, in which—

Figure 1 is a side view of one form of the invention shown in position on a watch; Fig. 2 is a front elevation thereof; Fig. 3 25 is a perspective view of the device removed from the watch; and Fig. 4 is a perspective view of a modified form of the invention applied to a book.

In the form of the invention shown in 30 the first three figures, it is shown as comprising a frame 10 formed of a single integral piece of wire and having two downwardly extending legs 11 substantially parallel with each other. At the top the two legs are connected by the wire, and this connection is employed in the form shown in these three figures for connecting the frame with the watch. For this purpose the upper part of 35 the frame is provided with a loop 12 adapted to clasp the neck of the watch as indicated in Figs. 1 and 2. The two legs of the frame are held together by a sheet metal strap 13, and they are also shown in this instance as being connected by a flexible 40 sheet of material 14, wrapped around the two legs of the frame and stretched across the intervening space. From the bottom of the legs two integral wire arms 15 extend upwardly and outwardly, and at their upper 45 ends they are provided with loops 16 which are embedded in the edge of a rubber pad

17. This pad is shown as roughened on the outer surface so as to provide projections thereon for engaging the inside of the outer wall of the pocket and holding the article 55 therein.

In the form of the invention shown in Fig. 4 the construction is of a similar character, but the parallel legs 21 of the frame 20 are connected across the top by the 60 straight integral bar 22. The frame is connected with the book or the like by means of clips 23 which surround the wire of the frame and have ends inside adapted to bend outwardly in a well-known manner. The 65 other parts are substantially the same as shown in the first three figures, but the fabric 14 is omitted. It will be seen that with the article and retaining device placed in the pocket the rubber pad will press 70 against the pocket and if an attempt is made to remove the article it will simply result in forcing the pad farther out and cause pressure to be applied so that the owner will feel it and notice that the article is 75 being abstracted. In this way losses due to accident and theft will be substantially prevented.

While I have illustrated and described two embodiments of the invention, I am 80 aware that many modifications can be made therein by any person skilled in the art without departing from the scope of the invention as expressed in the claims. Therefore I do not wish to be limited to all the 85 details of construction herein shown and described, but

What I do claim is:—

1. As an article of manufacture, a watch guard, comprising a frame made of wire 90 having horizontal means on the top for engaging the watch stem, parallel legs extending downwardly therefrom uniformly spaced apart throughout their length, and adapted to lie along the surface of a watch, an arm 95 extending upwardly and outwardly from the bottom of each of the legs, a pad on the upper ends of said arms, and a sheet metal strip connecting the lower ends of said legs.

2. As an article of manufacture, a device 100 for retaining articles in the pocket comprising a downwardly extending frame having

means thereon for securing it to the article to be retained, two integral flexible arms extending upwardly and outwardly from the bottom of the frame, and a rubber pad secured to the ends of said arms in position to engage the outer wall of the pocket.

5 In testimony whereof I have hereunto set

my hand, in the presence of two subscribing witnesses.

IVAR G. BERGENSTROHLE.
